Primary Examiner—Antoine Duval Davis(74) *Attorney, Agent, or Firm*—W. Scott Carson**CLAIM**

The ornamental design for an ankle joint for an ankle foot orthosis, as shown.

DESCRIPTION

FIG. 1 is a perspective view of an ankle foot orthosis showing my new design.

FIG. 2 is a front elevational view thereof.

FIG. 3 is a right side elevational view thereof, the left side elevational view being a mirror image thereof.

FIG. 4 is a top plan view thereof taken from FIG. 5.

FIG. 5 is a rear elevational view thereof; and,

FIG. 6 is a bottom plan view thereof taken from FIG. 5.
